UNITED STATES PATENT OFFICE.

FRANK W. PEEK, JR., OF SCHENECTADY, NEW YORK, ASSIGNOR TO GENERAL ELECTRIC COMPANY, A CORPORATION OF NEW YORK.

SEPARATION OF LIQUID SUSPENSIONS.

1,170,184.

Specification of Letters Patent.

Patented Feb. 1, 1916.

Application filed February 18, 1913. Serial No. 749,117.

To all whom it may concern:

Be it known that I, FRANK W. PEEK, Jr., a citizen of the United States, residing at Schenectady, in the county of Schenectady, 5 State of New York, have invented certain new and useful Improvements in Separation of Liquid Suspensions, of which the following is a specification.

The present invention relates to the separation of particles or globules of one liquid in another liquid. With particular reference to the separation of suspended water from oil. It has been suggested heretofore to separate emulsions of this nature by introducing them between high potential electrodes but this method gives trouble due to the formation of chains of globules between the electrodes, thus producing short-circuits. In accordance with my invention, this undesirable effect is avoided by introducing the liquid to be treated into an apparatus having a chamber traversed by an electrostatic field of unequal intensity and constructed so that the suspended particles are driven 25 by the electrostatic field against a wall of dielectric material where they collect and are thus removed.

My invention will be better understood by reference to the accompanying drawing, 30 which shows a sectional view of the apparatus.

The liquid to be treated, which we may assume to be oil containing suspended water particles, is introduced from a receiving tank 1, into a treating receptacle 2, which preferably consists of glass, porcelain, or other dielectric material. This receptacle is conveniently closed at each end by means of stoppers 3 and 4 and is provided with 35 an outlet tube 5 for the removal of the purified oil, and an outlet tube 6 for the removal of the separated water. The treating chamber is provided upon the outside with an electrode 7 consisting of tin foil, electrolytically deposited copper, or the like. The oil is conveyed into this treating chamber by means of a valve controlled tube 8 which discharges into a metallic tube 9 extending into the treating chamber and constituting 40 the coöperating electrode. As indicated, this inner electrode is preferably provided with sharp projections. It is separated a greater distance from the outer electrode at its ends than at the region where the projections are 45 provided and where the separating action

takes place. The oil is discharged into the lower part of the treating chamber and in rising to the discharge tube 5, passes through the electrostatic field created between the electrodes by some suitable source of high 60 potential electricity, for example, a high potential transformer 10. This arrangement gives a very dense, electrostatic field, of high gradient near the inner electrode but of relatively low gradient at the glass surface. 65

When oil containing colored water is introduced into the apparatus the following action may be clearly observed by the unaided eye. The water being a better conductor than oil, or considered in another aspect as having a much higher permittivity than oil, should be caused to move toward the stronger field. It is found, indeed, that the water particles move toward the inner electrode and upon closely watching it, it 75 may be plainly seen that a small spark passes to each drop before it touches the electrode. It is then quickly repelled to the outer electrode with considerable force. As the electrostatic field at the outer electrode 80 is not as intense as at the inner electrode due to its greater surface the drop sticks to the dielectric surface and is not again repelled but held there by the surface tension of the drop. The drops collect in this manner and slowly run to the bottom of the tube. 85

By passing oil containing water through the apparatus as above described with a potential of 15000 volts applied between the 90 electrodes, I have found the disruptive voltage of the oil to be increased from 23 to 52 kilivolts using in each case a standard gap at constant spacing for comparison.

The dielectric wall is also useful in preventing a short-circuit by a dynamic arc following a spark over, as when the oil is very bad.

What I claim as new and desire to secure by Letters Patent is:—

1. The combination in an apparatus for separating and collecting particles of one liquid suspended in another, of a pair of electrodes connected to a high potential source of electricity, one of said electrodes having its surface provided with projecting conductive points, and means for passing the liquid mixture between said electrodes. 105

2. The combination in an apparatus for separating particles of one liquid suspended 110

in another differing therefrom in conductivity, of a pair of electrodes, means for passing the liquid mixture between said electrodes, means for establishing an electrostatic field in the liquid between said electrodes which will be of high intensity at certain points and of much lower intensity at other points and a wall of dielectric material for preventing the formation of an arc between said electrodes.

3. In an apparatus for removing suspended water from oil, a glass vessel, an electrode coating upon the outside of said vessel, a metallic tube constituting another electrode in said vessel, said tube having its surface provided with projecting conductive points, means for passing the oil containing water through said tube into said vessel, and means for applying an alternating current of high potential to said electrodes.

4. The combination in an apparatus for separating particles of one liquid from a less conductive liquid in which they are suspended, of a vessel having a wall of dielectric material, an electrode having a plain surface upon the outside of said wall, an electrode upon the inside of said wall and spaced therefrom having a plurality of projecting conductive points and means for passing the liquids to be separated between said electrodes.

5. The combination in an apparatus for

removing suspended water from oil, of a vessel having a wall of dielectric material, an electrode coating on the outside of said wall, a hollow metallic electrode within said vessel spaced from said wall and provided with a plurality of projecting conductive points on its outer surface, means for passing the oil containing water into said vessel through the lower end of said electrode, means for withdrawing the oil from the top of said vessel, means for withdrawing the separated water from the bottom of said vessel and means for applying a high electrical potential to said electrodes.

6. The combination in an apparatus for separating particles of one liquid suspended in another differing therefrom in conductivity, of a wall of dielectric material, an electrode on each side of said wall, means for passing the liquid mixture between said wall and one of said electrodes, and means for establishing an electrostatic field in the liquid which will be of high intensity at certain points near said electrode and of much lower intensity at points near said wall.

In witness whereof, I have hereunto set my hand this 17th day of February, 1913.

FRANK W. PEEK, JR.
